UNITED STATES PATENT OFFICE.

HAROLD GROBMAN, OF BROOKLYN, NEW YORK.

DESIGN FOR A LAMP SHADE.

Application filed October 8, 1928. Serial No. 28,407. Term of patent 3½ years.

To all whom it may concern:

Be it known that I, HAROLD GROBMAN, a citizen of the United States, residing at Brooklyn, in the county of Kings and State of New York, have invented a new, original, and ornamental Design for Lamp Shades, of which the following is a specification, reference being had to the accompanying drawing, forming part thereof.

Fig. 1 is a top view.

Fig. 2 is a front view.

I claim:

The ornamental design for a lamp shade, as shown.

HAROLD GROBMAN.
